UNITED STATES PATENT OFFICE.

PAUL KUNIN AND REUBEN A. OLSEN, OF MINNEAPOLIS, MINNESOTA; SAID OLSEN
ASSIGNOR TO SAID KUNIN.

HAIR-CURLING APPARATUS.

Application filed January 18, 1926. Serial No. 81,941.

This invention relates to apparatus for treating and curling hair and is especially adapted for use in machines effecting a so-called permanent wave upon human hair. In 5 such apparatus it is desirable to employ a plurality of depending heating units or curlers supported from an overhead chandelier or bracket for convenient manipulation, each capable of being adjusted vertically as 10 desired.

Most commercial devices of this nature provide a plurality of counter-weighted heating units passing over overhead pulleys or guides. These devices utilize flexible 15 electrical connections extending from the bracket to the several heating units and moreover, require flexible members connected to the heating units and the counter-weights. Due to this structure the heating 20 units often become tangled with the several cords and electrical conductors, as well as the counter-weights, often causing considerable trouble to the operator.

It is an object of this invention to provide 25 simple but highly efficient apparatus for supporting a plurality of curling or heating units without the use of counter-weights or spring operated spools whereby each unit may be vertically adjusted independently 30 and maintained for operation at various heights.

A further object is to provide hair curling 35 apparatus equipped with independently adjustable heating units provided with means for closing an electric circuit in each heating unit when said unit is extended or lowered into operative position.

Another object of the invention is to compactly enclose all the electrical connections, 40 contacts and working parts within a decorative housing or dome readily removable to gain access to said parts, the only parts of said apparatus extending on the outer side of the dome or chandelier being the heating units and the electric conductors connected to the same.

A more specific object of the invention is 45 to provide for each heating unit a spring controlled swingable arm disposed within said dome adapted to vary the take-up on the flexible electrical conductors supporting the heating units. This construction permits the several heating units to be adjusted vertically and independently.

50 These and other objects of the invention

will be apparent from the following description made in connection with the accompanying drawings, wherein like characters refer to similar parts throughout the several views.

Figure 1 is a side elevation of an embodiment of the invention with the heating units raised to inoperative position. 60

Figure 2 is a horizontal cross section taken on a larger scale on line 2—2 of Figure 1. 65

Figure 3 is a vertical section taken on the line 3—3 of Figure 2.

Figure 4 is a horizontal section taken on the line 4—4 of Figure 3 showing a means of pivoting the swingable arms and the connection of the electric control element therewith. 70

Figure 5 is a detailed vertical section showing a means for making and breaking the circuit of one of the electric heating 75 units.

Figure 6 is a vertical section taken on the line 6—6 of Figure 1, showing the mechanism for raising or lowering the upright standard. Figure 7 is a vertical section of 80 the top portion of one of the heating devices.

Referring to the drawings by reference characters, an upright tubular standard 10 is rigidly carried by a heavy pedestal or base 11. A shaft or standard 12 is telescoped 85 within the tubular standard 10, means being provided which will later be described for elevating or lowering standard 12 relatively to lower standard 10. Standard 12 carries a T-head 13 at its upper end having rigidly 90 secured thereto by means of set screw 13^a an annular horizontal extending member 14. The annular member 14 is obviously capable of horizontal adjustment in T-head 13. A concave disk or frame 15 is seated in an 95 annular member 14 and supported thereby, an annular flange being provided at its upper peripheral edge. Centrally disposed in the bottom of frame 15 is an upstanding truncated conical drum 16 having in the upper 100 edge thereof a plurality of circumferentially spaced slots 16^a.

The inner ends of a plurality of radially disposed arms 17 are pivoted to drum 16 in said slots 16^a preferably by means of a wire 105 ring 18. Ring 18 passes through apertures in the inner ends of said arms located on the outer sides of the longitudinal center lines of said arms. As illustrated, the outer or free ends of said arms are bent backwardly 110

upon themselves to afford means for pivoting small pulleys 19 thereto. A relatively small coiled spring 20 or other elastic member is interposed between the inner end of 5 arm 17 and the base of drum 16. The springs 20 are attached to the arms at points on the inner sides of the longitudinal center lines thereof and are tensioned only slightly when the arms are swung upwardly.

10 A plurality of flexible casings 21 in which electric service wires are housed are anchored at their inner ends to a plurality of circumferentially spaced insulated posts 22 secured to the bottom of disk frame 15. The 15 bight of each of the flexible members 21 is passed over its appropriate pulley 19 on one of the arms 17 and has its free end passed through one of a plurality of eyes 23 or guide members circumferentially arranged 20 in a circle circumscribed about the anchor posts 22. The electric heating units, indicated by the letter A, are each secured and electrically connected to the free end of one 25 of the flexible conducting members 21 on the under side of disk frame 15. A dome or housing X fits over the lip of frame 15 enclosing all working parts.

The electrical connections to the heating units A are made as follows: lead wires 24 30 connected through a switch 25 to a source of electricity and connected respectively to upper and lower contact rings 26 and 27, which rings are mounted in frame 15 concentric to hub 16. Rings 26 and 27 are insulated and spaced apart by means of a plurality of circumferentially arranged posts 28, secured in upright position to the bottom of disk frame 15. Each of the heating units A is provided with service wires 29 35 encased within flexible member 21, one of said service wires being connected and anchored to the contact ring 27, the other of said service wires 29 being anchored and connected to the movable or spring contact 30 40 rigidly secured at one end to the top of one of the insulated posts 22. Each of movable contacts 30 extends inwardly over the top of upper contact ring 26 having its inner or 45 free end apertured to receive the lower turned end of a link 31. The upper end of link 31 is pivoted to the appropriate arm 17 at a point adjacent the pivoted end thereof. As illustrated in Figure 3, when the arms 50 17 are swung to upright or approximately upright position, through the action of 55 springs 20 the bight or slack in flexible members 21 will be taken up, the heating units A will be at elevated inoperative positions and the movable contacts 30 will be lifted by 60 links 31. The dotted lines in Figures 3 and 5 show the flexible member 21 extended to lower the heating unit A with arm 17 swung outwardly, thereby permitting contact 30 to close the circuit through its heating unit.

65 Mechanism is provided for readily elevat-

ing or lowering the frame as desired. This mechanism comprises a substantially rectangular casing 32 rigidly secured to the upper portion of lower standard 10 having journaled therein a shaft 33 on which is rigidly secured an operating sprocket 34 engaging a preferably notched rack 35 formed on the surface of upper standard 12 adjacent thereto. A worm gear 36 also rigidly secured to shaft 33 mounted within housing 32 is engaged by horizontally extending worm 37 journaled in said frame. The shaft of worm 37 extends through casing 32 and carries at its outer end the crank 38 by which it may be readily seen, movable standard 12 carrying the dome and frame may be raised or lowered.

The heating units may be of any desired standard type having the inner tubes in which the curling rods containing the hair are inserted and having the heat coils encircling said tubes. In Figure 7 the upper portion of one of the heating devices employed is shown in vertical section. The vertically disposed tubular member 39 fits snugly within an upper casing 40 of heat resistant material. Tubular casing 40 is provided with grooves to receive and house the service wires 29 which are electrically connected to the heat element at an intermediate portion of the heating device (not shown). An outer relatively thin tubular casing 42 is snugly telescoped over casing 40. The upper extremity of tube 39 is tapered and provided with a pair of vertically extending oppositely disposed slots 39^A in the upper portion thereof. These slots are adapted to receive the widened flat end 41^A of a curling rod 41 to permit the same to pass through the tapered portion of tube 39. When the flat head 41^A has been passed above the upper extremity of the tube 39, curling rod 41 is then turned to lock and center the same within said tube. Notches are provided in the top peripheral edge of the tapered portion of tube 39 wherein head 41^A is seated and retained.

The above described means for securing the curling rod in the several heaters not only permits the rods to be quickly inserted and locked within the heating tubes, but moreover centers the rod with respect to its surrounding tube.

Operation.

The operation of the above described device may be briefly set forth as follows:

Assuming the upper standard 12 and dome X to have been adjusted as desired by means of the mechanism previously described, the person whose hair is to be treated is seated directly beneath the disk frame 15. Strands of hair are then wound about curling rods and secured thereto and the switch 25 turned on. Before each strand of hair is inserted

within one of the heating units A the flexible conduit 21 must be pulled down, thereby releasing flexible contact 30 which closes the circuit for its heating unit. The strand of hair is then inserted within a heating unit disposed just above the head of the person treated. Obviously, when flexible member 21 is pulled down, arm 17 will be swung outwardly and downwardly. There will be sufficient friction on the parts and weight in the heating unit to balance the slight tension on spring 20. This device for varying the vertical position of the respective heating units has been thoroughly tested out and found highly efficient for the purposes intended. The sides of dome X are arched substantially concentrically with the arcs formed by the movement of the several arms 17.

It will be noted that arms 17 are properly spaced apart and can never strike each other, since they are guided by their pivots and are mounted in radial slots in the top edge of drum 16. The links 31 (see Figure 4) are insulated from arms 17 so that there will be no chance of a short circuit through the frame.

Heating units A are entirely supported by the flexible members 21, no additional cords, counter-weights or spools being needed to permit vertical adjustment of the same.

Dome X fits over the upper lip of disk frame 15 and may be readily secured thereto by any suitable means, such as set screws. Obviously, this dome may be readily removed to expose the take-up apparatus for the heating units as well as all electrical connection and contacts.

From the above description it will be seen that the applicant has invented a simple and highly efficient permanent wave apparatus rendering the greatest convenience and safety to the operator and dispensing with many objectionable features now included in most commercial devices of this type.

It will of course be understood that various changes may be made in the form, details, proportions and arrangement of parts without departing from the scope of the invention.

What is claimed is:

1. In apparatus of the character described an overhead support, a swingable arm pivoted to said support, a pulley or guide member adjacent the free end of said arm, a flexible member anchored at one end to said support and passed over said guide member with its free end depending from said support and a heating device attached to the free end of said flexible member whereby the vertical position of said heating device may be varied with the radial position of said arm.

2. In apparatus of the character described an overhead support, a plurality of radially disposed vertically swingable arms pivoted to the top side of said support, each of said arms having a pulley or guide member adjacent its free end, a plurality of flexible members anchored at their inner ends to said support passing over said guide members and having their free ends depending from said support and a plurality of independent electrical heating devices attached to the lower ends of said flexible members, and means impelling said arms to substantially upright position, the weight of said heating devices tending to counter balance the effect of said last mentioned means. 80

3. The structure set forth in claim 2 and said last mentioned means comprising elastic elements eccentrically connected to the inner ends of said arms and said support.

4. In apparatus of the character described an overhead support, a plurality of radially disposed vertically swingable arms pivoted to the upper side of said support, each of said arms having a pulley or guide member adjacent its free end, a plurality of circumferentially spaced eyes or guide members in said support aligned respectively with said radial arms, a plurality of flexible members anchored at their inner ends to said support and passed through said pulleys on said arms and said eyes in said support and a plurality of independent heating devices attached to the outer ends of said flexible members on the under side of said support. 100

5. The structure set forth in claim 4, said arms being pivoted at the outer sides of their longitudinal center lines and a plurality of elastic members each connected at one end to the pivoted end of one of said arms at a point on the inner side of the longitudinal center line thereof and having its other end secured to said support. 105

6. In apparatus of the character described an upright pedestal, a vertically movable standard mounted in said pedestal, a horizontally extending housing supported from the upper end of said movable standard, a plurality of independent heating devices suspended from said housing and vertically adjustable means for varying the height of said standard comprising a sprocket journaled in said pedestal and having engagement with teeth on said standard and a crank operated worm adapted to drive said sprocket. 110

7. In apparatus of the character described, an elevated support, a flexible member anchored at one end to said support and having its free end depending therefrom, a heating device secured to the free end of said flexible member, and swingable adjusting means pivoted to said support adapted to engage the intermediate portion of said

flexible member and to permit said flexible member to slip longitudinally thereover, whereby vertical position of said heating device may be varied according to the radial position of said swingable means.

8. In apparatus of the character described, an elevated support, a flexible supporting member anchored at one end to said support and having its free end depending therefrom, a heating device secured to the free end of said flexible member, a rigid member swingable on said support having means thereon for engaging the intermediate portion of said flexible member to permit longitudinal slippage of the same thereover, whereby the vertical position of said heating device may be varied with the radial position of said swingable member.

9. In apparatus of the character described, an elevated support, a flexible supporting member anchored at one end to said support, and having its free end depending therefrom, an electrical heating device connected to the depending end of said flexible member, swingable means on said support for varying the vertical position of said heating device, an electrical contact mounted on said support and electrically connected to said heating unit, and an electrical contact mounted on said swingable means in position to engage said first mentioned contact to close a circuit through said heating

device when said heating device is lowered to predetermined position.

10. In apparatus of the character described, an elevated support, a plurality of independent electrical heating devices suspended from said support, means for rendering said heating devices independently and vertically adjustable, and means connected to said first mentioned means for independently causing an electrical circuit to be closed through each heating device when said heating device is lowered to a predetermined position.

11. In apparatus of the character described, an elevated support, a plurality of independent circumferentially arranged electrical heating devices suspended from said support, a plurality of means on said support for independently varying the vertical position of said heating devices, a fixed annular contact electrically connected to a source of electricity, and a plurality of movable contacts, each connected to one of said adjusting mechanisms and each adapted to engage said annular contact when its heating device is lowered to a predetermined position.

In testimony whereof they affix their signatures.

PAUL KUNIN.
